UNITED STATES PATENT OFFICE

132,533

DESIGN FOR A STIRRUP PUMP

Daniel Kelleher, Strongsville, and Herman J. Troche, Cleveland Heights, Ohio, assignors to The American Coach & Body Company, Cleveland, Ohio, a corporation of Ohio

Application February 20, 1942, Serial No. 105,918

Term of patent 14 years

To all whom it may concern:

Be it known that we, Daniel Kelleher and Herman J. Troche, citizens of the United States of America, residing at Strongsville and Cleveland Heights, respectively, both in the county of Cuyahoga, State of Ohio, have invented a new, original, and ornamental Design for a Stirrup Pump, of which the following is a specification, reference being had to the accompanying drawing, forming part thereof.

Fig. 1 is a perspective view of a stirrup pump, showing our new design;

Fig. 2 is a rear elevational view thereof;

Fig. 3 is a sectional view taken on line 3—3 of Fig. 1; and

Fig. 4 is a cross-sectional detail view of the supporting bracket on line 4—4 of Fig. 1.

The dominant features of the design reside in the portions shown in full lines.

We claim:

The ornamental design for a stirrup pump, substantially as shown and described.

DANIEL KELLEHER.
HERMAN J. TROCHE.
